AUTOMATIC CUTTER

John R. McLaughlin, New Brunswick, N. J., assignor, by mesne assignments, to Tampax Incorporated, New York, N. Y., a corporation of Delaware

Application October 23, 1942, Serial No. 463,095

13 Claims. (Cl. 164—68)

1

This invention relates to apparatus for automatically forming compressed form-sustaining wads of absorbent cotton or the like for use for sanitary purposes, and said apparatus more specifically relates to devices which are coordinated with a sewing machine and adapted to sever the withdrawing string which is employed in certain types of these sanitary articles.

Prior to being compressed, and when leaving the sewing machine the cotton or other material has been cut into elongated pieces with the fibers disposed transversely, and these pieces have been stitched longitudinally in spaced relation to each other with a connecting string between them. Upon leaving the sewing machine, and prior to being operated upon by a compressing and forming apparatus, the attached pieces in the form of a continuous strip are passed through devices which are adapted to sever the string close to an end of each piece, thus leaving a "tail" attached to each piece. The present apparatus is designed for the purpose of accurately and effectively performing this severing operation.

An object of my present invention is to provide a machine that is adapted to rapidly, successively, and efficiently sever the withdrawing string close to an end edge of each piece of absorbent material, and to do this without injury to the respective pieces while they are being operated upon.

Another object is to perform the cutting operation automatically and without interference with the continuous operation of the apparatus which sews the strings.

Still another object is to provide an apparatus which is capable of being readily coordinated with the sewing machine, or with the compressing and forming apparatus, or both, while my present apparatus is operating in a continuous manner.

The above-mentioned, as well as other objects, aims, and advantages of my improvements, will be obvious to persons skilled in the art after the construction and operation of my apparatus is understood. It may be mentioned that it is an aim to provide an apparatus of novel construction; dependable in use; capable of being readily assembled when being manufactured; and is efficient in performing the functions for which it may have been devised.

It is preferred to accomplish the objects and aims of my said invention, and to practice the same, in substantially the manner hereinafter fully described, and as more particularly pointed out in the appended claims.

2

In connection with the present disclosure, reference is herein made to the accompanying drawings which form a part of this specification.

In the drawings:

5 Figure 1 is a side view in elevation of an apparatus which embodies the features of my invention.

10 Figure 2 is a fragmentary sectional view in elevation taken transversely through the structure shown in Figure 1 substantially along line II—II of Figure 1, looking in the direction of the arrows.

15 Figure 3 is a perspective view of a rotary string cutter holder utilized in the device shown in Figures 1 and 2.

20 Figure 4 is a perspective view of a blade-retaining plate used in connection with the holder shown in Figure 3.

25 Figure 5 is a plan view of a blade of the type it is desired to employ in connection with the elements herein shown in Figures 3 and 4.

30 Figure 6 is a top plan view of the apparatus disclosed in Figure 1.

35 Figure 7 is a perspective view of the gear indexing roller utilized in conjunction with the assembled apparatus shown in Figures 1 and 6.

Figure 8 is a vertical side elevation of the apparatus, portions of which are in section substantially along line VIII—VIII of Figure 6.

30 Figure 9 is a fragmentary sectional view taken substantially along line IX—IX of Figure 6, drawn to a larger scale.

Figure 10 is a diagrammatic plan view showing the position of severing successive strips of cotton having a stitched connecting string therebetween after leaving the sewing machine, and showing the string severed at one of the strips.

Figure 11 is a fragmentary sectional view taken substantially along line XI—XI of Figure 6.

40 Figure 12 is a fragmentary plan view taken substantially upon the plane of line XII—XII of Figure 8.

Figure 13 is a perspective view of a cam follower shown at the lower portion of Figure 12.

45 Figure 14 is a sectional view taken substantially along line XIV—XIV of Figure 12.

Figure 15 is a vertical transverse sectional view taken substantially along line XV—XV of Figure 8.

50 Figure 16 is a perspective view of a trip lever such as shown in assembled association in Figure 12.

The drawings are understood to be more or less schematic for the purpose of illustrating a typical or preferred form of my invention, and in said

drawings the same reference characters are used to identify the same parts throughout the diverse views.

The apparatus which is disclosed herein is mounted in a suitable supporting structure comprising a horizontal base A, having feet B, and provided with spaced parallel plates C, C', arising vertically from said base to provide mountings and bearings for the instrumentalities of the apparatus. A lateral extension A' projects to one side of the feed or front end of the base A, upon which extension a suitable speed-reducer D is mounted and driven by a shaft E receiving motion from a driving pulley E' that is actuated from any suitable source. A transmission shaft E2 is connected by a clutch device E3 to the main shaft 10 of the apparatus that is mounted in the vertical plates C, C'.

Suitable vertically disposed guide plates 11, that are flared away from each other at their outer ends, extend longitudinally between the vertical plates C, C' from the front towards the rear of the structure for the purpose of guiding and preventing lateral displacement of the articles or strip of material that moves through the machine, and a conveyor apron 12 receives the articles after they have been operated upon between the guides 11 and conveys the separated articles away from the apparatus.

The conveyor apron 12 travels upon an inclined bed 13 secured to upwardly extending arms 14 that are preferably removably connected to the discharge end of the apparatus, and said apron 12 passes around a pulley 15 at the lower end of the bed 13, that has its spindle 16, which is journaled in said arms 14, provided with an extended end carrying a sprocket 17 that is driven by a chain 18.

The main shaft 10 is provided with a sprocket 19 that is engaged with a chain 20 extending towards the discharge or rear end of the apparatus where said chain 20 engages another sprocket 21 on the adjacent end of a jack-shaft 22 journaled in the vertical plates C, C' through the medium of a sprocket 23 upon the other end of said jack-shaft 22 and is also engaged with the chain 18, whereby the apron-engaged pulley 15 is actuated at substantially the same speed as the pulley 24 that is secured to the jack-shaft 22 between the vertical plates C, C'. The apron bed 13 and supporting arms 14 may be an independent structure that is detachably connected to the delivery or rear end of the apparatus as detailed in Figure 11. The lower ends of said arms 14 are provided with downwardly opening slots 14a that embrace adjacent portions of the pulley spindle or shaft 22 which permits the structure being lifted off the machine. The intermediate portions of the arms 14 have supports 14b movably connected to them by pivot members 14c.

About midway the length of the vertical plates C, C' there is a small pulley 25 about which an apron 26 is engaged and which is driven by the pulley 24 on the spindle or shaft 22 that extends between the vertical plates C, C' and is journaled therein for rotation. Said apron 26 is disposed with its upper reach in a substantially horizontal plane as shown in Figure 9, and there is a small idle pulley 27 engaged with the under surface of the apron 26 intermediate the pulleys 24 and 25 the purpose of which will be later explained. Pulleys 25 and 27 have their respective spindles, 28 and 29, suitably journaled in adjacent portions of the vertical plates C, C', the pulley 25 being freely rotatable on its spindle 28. A tension pul-

ley 30, with its spindle 31 journaled in swinging arms 32, is adapted to maintain the apron 26 taut and take up any slack therein. The arms 32 are pivotally mounted at their lower ends on studs 33 projecting from the vertical plates C, C', and they are pulled in the desired direction by coiled springs 34, 34, that have their ends suitably connected to said arms and to lateral pins 35, 35 projecting from the inner faces of the vertical plates C, C', as shown in Figure 9.

Presser rollers 36, 36, are mounted above and in contact with the top reach or run of the apron 26 so that they normally will bear down upon the apron. The trunnions 37, 37 of these presser rollers 36, 36, rotate freely in upwardly opening vertical slots 38, 38, in carriers 39, 39, secured to the upper edges of the vertical plates C, C', and said rollers 36, 36, are preferably of solid construction of sufficient weight to firmly contact the pieces or wads of cotton as the latter successively pass beneath said rollers 36, 36 on the apron 26 while moving through the machine. When the wads of cotton engage the presser rollers 36, 36, the latter will be lifted as shown in dotted lines in Figure 9, and frictionally press down on said wads until the latter have passed said rollers 36 after which the rollers 36, 36, will each return to their apron-contacting positions as shown in the full lines in said figure.

The wads of cotton X are elongated and are provided with longitudinal stitching Y, and said wads are spaced apart suitable distances and are, when being fed into the machine, joined by a string Z which is a continuation of the stitching Y that is adapted to be severed as shown in Figure 10 during transit through the machine. The wads and the strings provide a continuous strip of material when fed into the apparatus.

At the front end of the machine there is a corrugated feed roller 40 that is fast on the horizontal main shaft 10 that has its end opposite the sprocket 19 provided with a gear 41. Coacting with this feed roller 40 is an opposing presser-roller 42 that has its spindle 43 carried in the free or swinging ends of elongated lever-arms 44 that incline downward towards the opposite end of the machine where their rear ends are secured to the spindle 28 upon which the apron-pulley 25 is loosely mounted for rotation. Said spindle 28 performs the function of a rock-shaft for actuating certain portions of the machine that control the timed operation of the cutter as later explained. The presser-roller 42 is yieldably urged towards the corrugated feed roller 40 by means of coiled springs 45, 45, that are connected at their upper ends to the projecting portions of spindle 43 and at their lower ends are engaged with lateral pins 46, 46 on the vertical plates C, C'.

A horizontal shaft 47 is journaled in bearings in the vertical plates C, C', with its end portions projected beyond said plates in the manner shown in Figure 2, and the intermediate portion of said shaft 47 has a roller 48 anchored to it for rotation therewith. This roller 48 is located between the corrugated-feed roller 40 and the apron pulley 25 so that the upper surface of said roller 48 is disposed in substantially the horizontal plane of the upper reach or run of the apron 26. Above and in vertical alignment with the axis of roller 48, there is a rotatable severing or cutting device which embodies a mutilated cylinder 49 secured to a rotatable shaft 50 that is journaled in the vertical plates C, C'. This cylindrical member 49 has a flattened portion 51 and it is also pro-

vided with an angular groove or notch 52 which provides a seat in which a blade 53 is secured by an adjustable clamping plate 54 so that the sharpened edge of said blade projects beyond the circumferential surface of said cylindrical member 49 in the manner shown in Figure 9 so that it will come into contactive engagement with the roller 48 when these portions of the machine are in operation.

The movement of the cutting cylinder 43 is timed so that the blade 53 will contact and sever the connecting string Z between the wads of cotton at a location close to the trailing edge of each wad as shown in Figure 10. The shafts 47 and 50 have gears 55 and 56 respectively that are secured to their extended ends and which are in mesh with each other so that they will be rotated in opposite directions and at the same speed. The roller 48 and the cutter member 49 are preferably adapted to be intermittently rotated for each severing or cutting operation performed by the blade 53, and when the wad X is between the roller 48 and the curved surface of cutter member 49 said wad will be in a compressed condition due to the fact that the space between the surfaces of these elements is preferably less than the thickness of a wad X.

The end of shaft 47 beyond its gear 55 has a cam element 57 secured to it, and the edge of said cam is provided with a notch 58 in which a small roller 59, rotatably mounted upon the adjacent end of a rocker-arm 60, is adapted to seat while the cutter rollers 48-49 are intermittently at rest or inactive. Said rocker-arm 60 is pivotally mounted for free movement upon the extended portion of the apron-roller spindle 28, and the end of said arm opposite its roller 59 is adjacent an electric switch operating button 61. A coiled spring 62, extending between the roller-carrying portion of the rocker-arm 60 and a pin 63 on the vertical plate C, maintains the opposite portion of said arm out of engagement with said switch-button 61 as shown in Figure 8, but when the roller 59 moves out of the notch 58 and engages the edges of cam 57 the arm 60 will be rocked to depress the switch-button 61 and thus maintain the latter in this position until the cam has made one revolution and the roller 59 has again seated in the notch 58.

The depressing of the switch-button 61 is adapted to form an electric circuit which will energize and actuate a solenoid 64 or the like, and the movement of the solenoid operates a lever 65 that is fulcrumed at one end on a post 66 arising from the base A and which, at its free end, is connected by a link 67 to the movable element of the solenoid 64. The shaft 47, which carries the cam 57 at one end, has its opposite end extended beyond the vertical plate C' and has a gear 68 loosely mounted on it in mesh with an idle gear 69 that is in mesh with gear 41 on the main shaft 10, so that the gear 68 will run free on its shaft 47, and said gear is maintained against longitudinal movement on shaft 47 by a shoulder 70 on the adjacent portion of said shaft.

A clutch member 71 is secured to said gear 68, and an opposing clutch member 72 is slidably mounted on and rotatable with said shaft beyond the shoulder 70. A tubular sleeve 73, formed with clutch member 72, surrounds shaft 47 and projects beyond the end thereof where it is provided with a conical head, the apex of which latter is engaged with the enlarged end 75 of an adjusting screw 76 carried in the adjacent portion of lever 65 and maintained in position by lock-nut 77. 75

The sleeve 73 has aligned slots 78 to receive the projecting ends of a transverse pin 79 that passes through said shaft 47, and a coiled spring 80 within the sleeve 73, between the end of shaft 47 and the inner end of the conical head 74, normally urges the clutch member outwardly on the shaft 47 and away from the clutch member 71.

When the solenoid 64 is energized, the lever 65 will swing inwardly and move the clutch member 72 into engagement with the other member 71, thereby connecting the power mechanism through gears 41, 69 and 68 to the shaft 47, causing the latter to rotate and turn the roller 48 and the cutter cylinder 49 through the instrumentalities of the gears 55 and 56. It is desirable that this operation be started prior to the disengagement of the roller 59 from cam notch 58, and this is readily accomplished by providing an elongated finger 81 projecting from a boss 82 that is secured to the rock-shaft 28 between the rocker-arm 60 and the vertical plate C'. This finger 81 is disposed alongside the portion of said arm 60 which projects towards switch-button 61, and it is of the same length as said arm portion just mentioned. 20 Thus, when the wad X enters between the advancing rollers 40-42 and lifts the latter roller 42, the carrier arms 44 thereof will turn the rock-shaft 28 causing the finger 81 to act as a detent or pawl and operate the switch-button 61, which 25 will actuate the clutch to start the rotation of the cutter devices. When the wad X passes beyond the advancing rollers 40-42, the latter roller 42 will drop back to normal position (Figure 9) and the finger 81 will be thereby disengaged from the switch-button 61. However, the rocker-arm 60 will continue to hold the button 61 depressed until the roller 59 has left the cam edge and has seated in the notch 58, whereupon the solenoid will be de-energized and the clutch elements 30 71-72 will be separated by the action of the spring 80.

Although the advancing or feed rollers 40-42 and the cutter devices 48-49, when operating, travel at the same number of revolutions per minute, the larger diameters of the cutter rollers 47-49 give them a higher peripheral speed than the feed rollers 40-42. This has the effect that when the cutting action takes place the part being cut is given tension by the higher surface speed of said cutter rollers. The drive of the apron 26 is so arranged that the lineal speed thereof is greater than the surface speed of the cutter-rollers 48-49. As the material passes beneath the roller 36, the friction of the material against the apron 26 will keep the material under tension, while the cutting action is taking place, to enable the blade 53 to sever the string Z completely and cleanly.

As the material enters rollers 40-42, the latter roller 42 raises, and this movement causes solenoid 64 to be energized, thus throwing the toothed clutch members into assembly to start the cutting rollers. The position of the blade 53 is adjustable in relation to the position of the cam-notch 58 so that after the blade has started to move it will engage the advancing material at the exact point when the string Z is to be cut. As the wads travel on the apron 26, which has a greater surface speed than the peripheral speed of the cutter rollers 48-49, the tension which is thus imparted to the strip of moving material causes the string to tighten so that it is cut cleanly and is definitely separated from the leading wad X close to the trailing edge thereof. After the cutter rollers 70 48-49 have made the cut, the clutch elements will

remain in engagement with each other through the medium of the edge of cam 57 holding the switch-button depressed until the cutter rollers have made one complete revolution and have returned to their starting position. The roller 59 dropping into cam-notch 58 will de-energize the solenoid and permit the clutch elements to become separated. The roller 42 at this moment will have returned to its normal position well ahead of the last-described movements of the apparatus, and the cutter members are again ready for the next 10 wad of the strip of material as it passes between the advancing rollers 40—42. The aforesaid cycle of operation will continue so long as the continuous strip of material is fed to the apparatus from the stitching machine.

While I have described my invention in detail in its present embodiment or preferred form, it will be obvious to persons skilled in the art, after understanding my invention, that various changes and modifications may be made therein without departing from the spirit or scope thereof. I aim in the appended claims to cover all such changes and modifications.

What is claimed is:

1. An apparatus for severing articles from a continuous strip, embodying continuously moving means for advancing the strip; continuously moving means for receiving the advanced portion of the strip; intermittently operable severing devices interposed between said advancing means and said receiving means; and electro-responsive means controlling the operation of said severing devices, said electro-responsive control means being timed responsive to the position of and having operable connection with a portion of said strip advancing means.

2. An apparatus for severing articles from a continuous strip, embodying means for advancing the strip; means for receiving the advanced portion of the strip; severing devices interposed between said advancing means and said receiving means; and means controlling the operation of said severing devices, said control means comprising a cam; a clutch connecting said severing devices to a drive mechanism; and means operatively connecting said clutch to said cam.

3. An apparatus for severing articles from a continuous strip, embodying continuously moving means for advancing the strip; continuously moving means for receiving the advanced portion of the strip; intermittently operable severing devices interposed between said advancing means and said receiving means; and means controlling the operation of said severing devices, said control means comprising a cam; a clutch connecting said severing devices to a drive mechanism; and means operatively connecting said clutch to said cam.

4. An apparatus for severing articles from a continuous strip, embodying opposed feed rollers for advancing the strip, one of said rollers being bodily movable towards and away from the other roller; means receiving the advanced portion of the strip and adapted to tighten the adjacent portion thereof; severing devices interposed between said rollers and said tightening means; and devices controlling the operation of said severing devices, said control devices having operable connection with said bodily movable roller.

5. An apparatus for severing articles from a continuous strip, embodying continuously moving opposed feed rollers for advancing the strip, one of said rollers being bodily movable towards and away from the other roller; continuously

moving means for receiving the advanced portion of the strip and adapted to tighten the adjacent portion thereof; intermittently operable severing devices interposed between said rollers and said tightening means; and devices controlling the operation of said severing devices, said control devices having operable connection with said bodily movable roller.

6. An apparatus for severing articles from a continuous strip, embodying opposed feed rollers for advancing the strip, one of said rollers being movable bodily towards and away from the other roller; means for receiving the advanced strip and adapted to tighten the adjacent portion thereof; severing devices interposed between said rollers and said tightening means; and devices controlling the operation of said severing devices, said control devices comprising a cam; a clutch operatively connecting said severing devices to a drive mechanism; and means operatively connecting said clutch to said cam.

7. An apparatus for severing articles from a continuous strip, embodying continuously moving opposed feed rollers for advancing the strip, one of said rollers being bodily movable towards and away from the other roller; continuously moving means for receiving the advanced portion of the strip and adapted to tighten the adjacent portion thereof; severing devices interposed between said rollers and said tightening means; and devices controlling the operation of said severing devices, said control devices comprising a cam; a clutch connecting said severing devices to a drive mechanism; and means operatively connecting said clutch to said cam.

8. An apparatus for severing a continuous strip having spaced enlarged portions, embodying opposed rotatable feed rollers adapted to continuously advance the strip, one of said rollers movable bodily away from the other roller when engaged with an enlarged portion of the strip; pivoted arms upon which said movable roller is mounted; intermittently operable severing devices spaced from said rollers in the line of travel of the strip; a drive-shaft operatively connected to and actuating said rollers; means operatively connecting said drive-shaft and severing devices; a clutch interposed in said means; electro-responsive devices for moving said clutch into active and inactive positions whereby said severing devices are intermittently actuated; and an indexing finger having operative connection with and actuated by said pivoted arms for controlling said electro-responsive devices.

9. An apparatus for severing a continuous strip having spaced enlarged portions, embodying opposed feed rollers adapted to continuously advance the strip, one of said rollers movable bodily away from the other roller when engaged with an enlarged portion of the strip; pivoted arms upon which said movable roller is mounted; a rock-shaft actuated by the movement of said arms; intermittently operable severing devices spaced from said rollers in the line of travel of the strip; a drive-shaft operatively connected to and actuating said rollers; means operatively connecting said drive-shaft and severing means; a clutch interposed in said means; electro-responsive devices for moving said clutch into active and inactive positions whereby said severing devices are intermittently actuated; and an indexing element secured to and actuated by said rock-shaft for controlling said electro-responsive devices.

10. An apparatus for severing a continuous strip having spaced enlarged portions, embodying

opposed rotatable feed rollers adapted to continuously advance the strip, one of said rollers movable bodily away from the other roller when engaged with an enlarged portion of the strip; pivoted arms upon which said movable roller is mounted; intermittently operable severing devices spaced from said rollers in the line of travel of the strip; a drive-shaft operatively connected to and actuating said rollers; means operatively connecting said drive-shaft and severing devices; a clutch interposed in said means; electro-responsive devices for moving said clutch into active and inactive positions whereby said severing devices are intermittently actuated; an indexing finger having operative connection with and actuated by said pivoted arms for initially controlling said electro-responsive devices; a cam rotated by said severing devices; and a rocker-arm engaged with and actuated by said cam, said rocker-arm adapted to control said electro-responsive devices subsequent to the effective operation of said indexing finger.

11. An apparatus for severing a continuous strip, embodying opposed feed rollers adapted to continuously advance the strip, one of said rollers movable bodily away from the other roller; pivoted arms upon which said movable roller is mounted; a rock-shaft actuated by the movement of said arms; intermittently movable severing devices spaced from said rollers in the line of travel of the strip; a drive-shaft operatively connected to and actuating said rollers; means operatively connecting said drive-shaft and severing devices; a clutch interposed in said means; electro-responsive devices for moving said clutch into active and inactive positions whereby said severing devices are intermittently actuated; an indexing finger secured to and actuated by said rock-shaft for initially controlling said electro-responsive devices; a cam actuated by said severing devices; and a rocker-arm engaged with and actuated by said cam, said rocker-arm adapted to control said electro-responsive devices subsequent to the effective operation of said indexing finger.

12. An apparatus for severing a continuous strip

5 embodying opposed rotatable feed rollers adapted to continuously advance the strip, one of said rollers movable bodily away from the other roller; pivoted arms upon which said movable roller is mounted; intermittently movable severing devices spaced from said rollers in the line of travel of the strip; an apron movable in the direction of travel of the strip; presser means coacting with said apron to maintain the strip in frictional contact therewith and also to tighten the strip between said apron and said rollers during cutting operation of said severing devices; a drive shaft operatively connected to and actuating said rollers; means operatively connecting said drive-shaft and severing devices; a clutch interposed in said means; electro-responsive devices for moving said clutch into active and inactive positions whereby said severing devices are intermittently operated; and an indexing member having operative connection with and actuated by said pivoted arms for controlling said electro-responsive devices.

13. An apparatus for severing a continuous strip embodying opposed feed rollers adapted to continuously advance the strip, one of said rollers movable bodily away from the other roller; pivoted arms upon which said movable roller is mounted; an apron movable in the direction of travel of the strip; means coacting with said apron to maintain the strip in frictional contact therewith and also to tighten the strip between said apron and said rollers during the cutting operation of the severing devices; a rock-shaft actuated by the movement of said arms; intermittently operable severing devices spaced from said rollers in the line of travel of the strip; a drive shaft operatively connected to and actuating said rollers; means operatively connecting said drive-shaft and severing devices; a clutch interposed in said means; electro-responsive devices for moving said clutch into active and inactive positions whereby said severing devices are intermittently actuated; and an indexing element secured to and actuated by said rock-shaft for controlling said electro-responsive devices.

JOHN R. McLAUGHLIN.
